(57) **ABSTRACT**

A harness for supporting a person working at height, including a back, leg loops, two forward connection arrangements and a flexible load-bearing member extending between the connection arrangements, which flexible load-bearing member carries a sliding attachment device attached to a climbing line. The forward connection arrangements transfers load from the back and the leg loops to the load-bearing member. Each forward connection arrangement includes: a body with apertures through which a leg riser webbing of the harness passes to connect the body to the back and the leg loops of the harness; and a bridge passage through which the flexible load-bearing member passes. A forward connection arrangement further includes a rope adjuster with a cam in the bridge passage. The cam pivots on an axle on the body. The cam cooperates with a locking surface of the body within the bridge passage to effect locking of a rope.

HARNESSES

This application claims priority to GB Patent Application No. 2101243.0 filed Jan. 29, 2021, the entire contents of which are hereby incorporated by reference.

BACKGROUND TO THE INVENTION

Field of the Invention

This invention relates to personal protective equipment and, more particularly, harnesses or components thereof. Particularly, but not exclusively, the invention relates to components used to make a harness suitable for use in supporting a person working at height using rope access and hardware (metal components) that are used within its construction. It also has application for a harness and hardware that are part of a fall-protection system, for example for use by a climber.

A harness may be designed to support a user when working at height, to provide a comfortable body support for performing tasks when suspended from a rope access system. Alternatively or additionally, a harness may be used to arrest a user's fall, for example in a fall protection system used by a climber where there is the potential for a fall. Embodiments of the invention might find application to hardware used for rope access, industrial height safety, rescue, tactical applications, sport climbing, etc. Within this specification, example embodiments will be described that relate to harnesses intended for use in tree care, but this should not be taken to be limiting upon the range of applications of the invention.

SUMMARY OF THE PRIOR ART

In EP-A-3 332 840, the present applicant disclosed a range of improved forward connection arrangements that improve upon the arrangements used in the harness of FIGS. 1a and 1b. In that publication, each forward connection arrangement comprises: a body that is permanently connected to the harness and a retention component that can be removably and rigidly connected to the body to removably secure the flexible load-bearing member to the body. Amongst several embodiments, forward attachment arrangements were proposed that include a rope adjuster whereby the effective length of the rope bridge can be changed.

An aim of the present invention is to implement forward connection arrangements that have the advantages of those disclosed in EP-A-3 332 840, and which are lighter, more compact or easier and less costly to manufacture.

SUMMARY OF THE INVENTION

To this end, the present invention provides a harness for supporting a person working at height, comprising a back, leg loops, two forward connection arrangements and a flexible load-bearing member that extends between the connection arrangements, which flexible load-bearing member carries a sliding attachment device which attaches to a climbing line, the forward connection arrangements serving to transfer load from the back and the leg loops to the load-bearing member, wherein each forward connection arrangement comprises:

- a body that has apertures through which a leg riser webbing of the harness passes to connect the body to the back and the leg loops of the harness,

2

b. a bridge passage through which the load-bearing member passes;

and wherein:

c. at least one forward connection arrangement further includes a rope adjuster, which rope adjuster includes a cam in the bridge passage, the cam being pivoted on an axle carried on the body and the cam is disposed to cooperate with a locking surface of the body within the bridge passage to effect locking of a rope.

10 Preferably, the rope adjuster includes a biasing spring disposed to bias the cam towards the locking surface.

This arrangement integrates the rope adjuster into the body, so reducing the number of components in the connection arrangement. This simplifies manufacture, and reduces the potential weakness associated with fasteners used to interconnect components.

Typically, the axle is located in a bore within the body.

The load-bearing member may be formed from an elongate member, such as a rope or a length or lengths of webbing. The load-bearing member may comprise two or more similar or different elongate members. In the latter case, each rope may pass through a respective bridge passage of the body, and there may be a rope adjuster in each bridge passage. The multiple cams of the rope adjusters typically arranged for rotation about a common axis. These may be carried on a common axle or on individual axles.

The body may include a projecting lug through which an attachment aperture passes.

Most typically the body is a one-piece metal component.

BRIEF DESCRIPTION OF THE DRAWINGS

FIGS. 1 and 2 show a harness incorporating a forward connection arrangement embodying the invention;

35 FIGS. 3 and 4 are views of a forward connection arrangement embodying the invention;

FIG. 5 is an exploded view of the embodiment of FIGS. 3 and 4;

40 FIGS. 6 and 7 are a sectional view of the embodiment of FIGS. 3 to 5;

FIGS. 8 to 10 are front, back and side views of a base component of the embodiment of FIGS. 3 to 7; and

45 FIGS. 11 and 12 are exploded views of a modified embodiment of the invention.

DETAILED DESCRIPTION OF THE PREFERRED EMBODIMENTS

Embodiments of the invention will now be described in detail, by way of example, and with reference to the accompanying drawings.

A harness of a type suitable for use with the present invention is shown in FIGS. 1 and 2.

The harness comprises two leg loops 10 that, in use, encircle a user's thighs. Each leg loop 10 is connected to a padded back 12 that rests against the small of a user's back and has side wings that extend to above a user's hips when in use. The back has a waist webbing 14 that has ends that can be interconnected by a releasable front waist buckle 16.

60 Each side wing has a side attachment arrangement 20. Each side attachment arrangement 20 connects the waist webbing 14 in the region of the wing through a riser webbing 18 through a respective side attachment arrangement to the corresponding leg loop 10. In this known arrangement, the side attachment arrangement 20 comprises two metal loops 22, 24 through which the waist webbing 14 passes.

The harness also includes two forward connection arrangements **30** as shown in FIG. 1 to suspend a flexible load bearing member **32** (also known as a "rope bridge") across the front of the harness. In this example, the rope bridge **32** includes two adjacent lengths of rope **32', 32"**. For use, the rope bridge **32** carries a sliding attachment device, a metal ring **34** in this embodiment, which is attached, for use, to a climbing line. These lengths of rope, in this embodiment, act together to transfer load from the ring **34** to the forward connection arrangements **30**, but in other embodiments may transfer load from the forward connection arrangements **30** to independent external anchorages. One or both lengths of rope could be replaced with a length of webbing.

FIGS. 3 to 10 shows a first example of a forward connection arrangement embodying the invention in more detail.

The forward connection arrangement **30** includes a body **50** formed as a single-piece metal component, which is intended to be permanently incorporated into the harness, for example, by sewing. (In this context, "permanently" means that it is not intended to be separated during normal use but may be replaced during repair or refurbishment) The body **50** has a generally oval or slight figure-of-eight peripheral shape and is formed from a single piece of metal by a combination of one or more of casting, forging and machining. The body **50** extends approximately in a plane **P**, having inner and outer surfaces disposed to opposite sides of the plane **P**, and its periphery can be considered as defining a region of the plane through which, multiple holes pass. The body is broadly symmetrical about an axis **A** that extends within the plane and that forms a long axis of the body **50**.

A pair of bridge passages **52', 52"** disposed to opposite sides of the axis **A** approximately one third of the distance along the axis **A** from a first end of the axis **A**, each bridge passage **52** extending through the body **50** approximately perpendicular to the plane **P**. Each bridge passage **52** extends from the inner surface of the body **50**, through the plane **P**, and then extends beyond the outer surface within a tubular formation of the body **50**. Each bridge passage **52** has a cross-sectional shape that has a flat base surface that extends perpendicular to the axis **A**, side walls **56** that extend from the base surface, and an arcuate outer surface that interconnects the side walls **56**. Adjacent side walls of the bridge passages **52', 52"** are formed by a common web **56'** within the body **50**. In the alternative, the common web **56'** may be omitted, with one or more elements **32', 32"** of the rope bridge **32** passing through a single rope passage.

A first and a second webbing slot **54', 54"** are disposed to opposite sides of the axis **A**. Each slot **54', 54"** extends from close to the axis **A** (that lies between the bridge passages **52', 52"**) and to a first axial end of the body **50**. Each slot **54', 54"** extends along an arc that is a constant distance from a proximal part of the periphery of the body **50**.

There is an attachment hole **60** that extends symmetrically about the axis **A** to partially surround the bridge holes **52', 52"** and to extend to a second axial end of the body **50**. This imparts the body **30** with a D-shaped attachment portion extending from the bridge passages **52** in a direction away from the webbing slots **54', 54"**.

All above-described holes and passages **52', 52"; 54', 54"**; **60** are formed with curved peripheries and without sharp corners to avoid the creation of stress risers within the body and within any object that is passed through the hole, and to minimise abrasion of any object that is passed through the hole.

A rope adjuster assembly is constructed within one or both bridge passage **52', 52"**, as will now be described.

An axle bore **62** extends across each of the bridge passages **52**, transverse to the axis **A**, being formed from 5 coaxial bores that pass through the side walls of the bridge passages **52', 52"**. A cylindrical cam axle **64** is located within the axle bore **62**, in which it is a close fit. A tapped bore extends axially into each end of the cam axle **64**. When installed, the cam axle **64** extends past each side wall **56** 10 through the common web **56'** of the body **50**. The cam axle **64** is retained in place by two bolts **66**, each being threaded into a respective one of the threaded bores of the cam axle **64**. A head of each bolt is received within an annular recess that surrounds each outer opening of the axle bore **62**. 15 Alternatively, the cam axle **64** may be of greater length, and be riveted in place in the bore, the bolts **64** being omitted.

Two cams **68', 68"** are carried on the cam axle **64** within a respective one of the bridge passages **52', 52"**. Each cam **68', 68"** has an axle bore **69', 69"** through which the cam axle **64** passes with a close fit and a gripping surface **70', 70"** that 20 faces generally away from the cam axle **64**, the gripping surfaces **70** being at a radial distance from the cam axle **64** that varies with the circumferential position of the surface **70** about the cam axle **64**. Multiple ridges extend across the 25 gripping surface **70**. An end portion of each cam **68** projects from the body **50** and a region **72', 72"** of the outer surface adjacent to the end portion is knurled.

A respective close-wound torsion spring **76', 76"** is associated with each cam **68', 68"**. Each spring **76** has active 30 coils surrounding the cam axle **64** within a recess of one of the cams **68** radially inwardly of the gripping surface **70**. The wire of each spring **76** is terminated with two legs that extend from the active coils parallel to the cam axle **64**. A first leg of each spring **76** is received in one of several holes 35 **78** that extends axially into the cam **68**, and a second leg is received within a slot **80', 80"** formed in a side wall of each bridge passage **52', 52"**, the slots opening to the outer surface of the body **50**, one slot **80"** being formed in the common web **56'**. The springs **76', 76"** serve to bias the cams **68', 68"** 40 in rotation in a direction around the cam axle **64** in a direction that the end portion of the cam **68** is urged towards the base of the bridge passage **52**; the cams **68', 68"** are oriented such that the radius of the gripping surface increases in that direction.

Each length of rope **32', 32"** of the rope bridge **32** passes 45 through a respective one of the bridge passages **52', 52"**, the rope bridge **32** extending between the inner surfaces of the bodies **50** of the two forward connection arrangements. The lengths of rope **32', 32"** and the bridge passages **52', 52"** are dimensioned such that the ropes **32', 32"** are a close fit within the passages **52', 52"** so that the ropes encounter the cams **68', 68"** at approximately a constant angle irrespective of the angle at which the ropes **32', 32"** enter and exit the bridge passages **52', 52"**. The gripping surfaces **70** of the cams **68', 55 68"** are urged into contact with the ropes **32', 32"** by the action of the springs **76', 76"**. If tension is applied to the inner length of the rope bridge **32** between the forward connection arrangements **30', 30"**, this will tend to cause the cams to rotate in the direction of action of the springs **76', 76"**, thereby tending to increase the effective radius of the gripping surface **70**, with the result that the ropes **32', 32"** are clamped between the gripping surfaces **70** and the base of the bridge passages **52', 52"**. An increase in tension in the rope bridge **32** will increase the clamping force such that 60 movement of the ropes **32', 32"** is prevented. If the ropes **32', 32"** are pulled from the outside of the forward connection arrangements **30**, the cams are turned against the action of 65

the springs 76', 76", thereby tending to decrease the effective radius of the gripping surface 70, with the result that the ropes 32', 32" are no longer clamped and can slide through the bridge passages 52', 52", shortening the effective length of the rope bridge 32.

If a user wishes to increase the effective length of the rope bridge 32, force can be applied manually to the projecting end portions of the cams and the adjacent knurled surface to rotate them against the action of the springs 76', 76" to reduce the force applied by the gripping surfaces 70 to the rope or until the gripping surface 70 come out of contact with the ropes 32', 32". The ropes 32', 32" can then be pulled through the body 50 in either direction.

In this embodiment, the body 50 further includes a lug 90 which is disposed between the webbing slots 54', 54" (or centrally of a single webbing slot), and projects generally perpendicularly from the plane P. A circular attachment aperture 92 passes through the lug 90. This can serve as an attachment for a connector for a load supporting platform in 15 embodiments of the invention disclosed and claimed in WO-A-2020/065279 of the present applicant. Such a lug is an optional feature of embodiments of this invention.

The embodiment of FIGS. 11 and 12 has an external appearance substantially identical to that of the preceding Figures and uses the same body 150 (with the exception that one slot 80' is omitted (a slot 180 in the common web 156 is present). This embodiment has a different internal construction, which will now be described.

In this embodiment, the cam axle 164 is a cylindrical metal rod with axial tapped bores formed into it from opposite ends. First and second axle retaining bolts 166', 166" are compatible with the threads formed in the cam axle 164.

The cams 168', 168" are handed and mirrored about the axis A. Each cam has an annular radial web that extends radially between the gripping surface 170 and the axle bore 169', 169". The web is recessed, the recess 171 (referred to as the spring recess) that is adjacent to the common web 156 being deeper than the opposite recess 173. A plurality of small holes 178 pass through the web parallel to the cam axle 164.

In this embodiment, each cam 168 is carried on the cam axle 164 by inner and outer cam bushes 182, 184. Each cam bush 182, 184 has a through bore that is a close fit on the cam axle 164. Each cam bush 182, 184 has a stepped outer surface, with a lesser diameter part that is a close fit in the axle bore 169 of the cam 168. The lesser diameter parts are inserted into the axle bore 192 and abut one another within the cam.

A single spring 176 has two sets of active coils surrounding the cam axle 64 within an inner recess 171 of a respective one of the cams 168 radially inwardly of the gripping surface. The sets of active coils are interconnected by a connecting leg and each set of active coils has a projecting terminating leg. The connecting leg is received within the slot 180 in the common web 156 to resist rotation of the spring 176 about the cam axle 164. Each terminating leg is received within a small hole 178 in a respective one of the cams 168.

In the completed assembly, each cam 168 is carried on its bushes 182, 184, which are, in turn, carried on the cam axle 164. Each set of active coils surrounds a respective one of the inner bushes 182. The axle retaining bolts 166', 166" are screwed into opposite ends of the axle through holes in the body 150.

In an alternative configuration, potentially applicable to any embodiment, the cam axle 64, 164 is retained in the

body by riveting its end and omitting the axle retaining bolt 60, 160. This can be done at one or both ends of the cam axle 64, 164.

What is claimed is:

5. 1. A harness for supporting a person working at height, comprising:
a back,
leg loops,
two forward connection arrangements, and
a flexible load-bearing member that extends between the connection arrangements,
wherein said flexible load-bearing member carries a sliding attachment device which attaches to a climbing line, the forward connection arrangements serving to transferring load from the back and the leg loops to the flexible load-bearing member, wherein each forward connection arrangement comprises:
a body that has apertures through which a leg riser webbing of the harness pass to connect the body to the back and the leg loops of the harness,
a bridge passage that extends through the body through which the flexible load-bearing member passes; and
wherein:
in at least one forward connection arrangement the body further comprises an integrated rope adjuster constructed within the bridge passage,
wherein the rope adjuster includes i) a cam in the bridge passage, the cam being pivoted on an axle carried on the body, and ii) a biasing spring disposed to bias the cam towards a locking surface of the body within the bridge passage to effect locking of the flexible load-bearing member.
2. The harness of claim 1 wherein the axle is located in a bore within the body.
3. The harness of claim 1 wherein the load-bearing member includes an elongate element.
4. The harness of claim 3 wherein the elongate element is a rope.
5. The harness of claim 3 wherein the elongate element is a length of webbing.
6. The harness of claim 1 wherein the load-bearing member includes two or more similar or dissimilar elongate elements.
7. The harness of claim 1 wherein the load-bearing member comprises two or more ropes.
8. The harness of claim 1 wherein each rope passes through a respective bridge passage of the body.
9. The harness of claim 8 having a rope adjuster in each bridge passage.
10. The harness of claim 9 wherein the cams of each of the rope adjusters are disposed for rotation about a common axis.
11. The harness of claim 10 wherein the cams of each of the rope adjusters are carried on a common axle.
55. 12. The harness of claim 1 wherein the body is a one-piece metal component.
13. The harness of claim 1 wherein the body includes a projecting lug through which an attachment aperture passes.
14. The harness of claim 1, further comprising:
an axle bore that extends across the bridge passage, transverse to an axis (A) that extends within a plane of the body and that forms an axis of the body,
the axle bore being formed by coaxial bores that pass through side walls of the bridge passage,
the axle being a cam axle located within the axle bore and extending past each side wall of the bridge passage, the cam axle being retained in place.

15. A harness for supporting a person working at height, comprising:
 a back;
 leg loops;
 two forward connection arrangements;
 leg riser webbing; and
 a flexible load-bearing member that extends between the connection arrangements,
 wherein said flexible load-bearing member carries a sliding attachment device which attaches to a climbing line,
 wherein the forward connection arrangements transfer load from the back and the leg loops to the flexible load-bearing member,
 wherein each forward connection arrangement comprises:
 a body that is a one-piece component, wherein the body has apertures through which the leg riser webbing pass to connect the body to the back and to the leg loops,

5

10

15

a bridge passage that extends through the body through which the flexible load-bearing member passes;
 a cam axle extending across the bridge passage;
 a rope adjuster cam carried by, and pivoting on, the cam axle, the rope adjuster cam having a gripping surface and a recess located radially inwardly of the gripping surface,
 wherein the bridge passage is sized to pass a length of the load-bearing member with the gripping surface of the rope adjuster cam facing an outer surface of the rope bridge; and
 a biasing spring, the biasing spring having active coils surrounding the cam axle and disposed within the recess of the rope adjuster cam, the biasing spring biasing the gripping surface of the rope adjuster cam towards the outer surface of the body within the bridge passage to effect locking of the flexible load-bearing member within the bridge passage.

* * * * *
